UNITED STATES PATENT OFFICE.

DONALD G. LITTLE, OF WILKINSBURG, PENNSYLVANIA, ASSIGNOR TO WESTINGHOUSE ELECTRIC & MANUFACTURING COMPANY, A CORPORATION OF PENNSYLVANIA.

CARRIER-CURRENT SIGNALING SYSTEM.

Application filed April 2, 1924. Serial No. 703,668.

This invention relates to radio-frequency systems for signaling over line conductors. Particularly, it relates to signaling by means of carrier currents.

- 5 · It is an object of this invention to take advantage of the properties of standing waves, such as are produced in long lines by the application of high-frequency energy thereto.
- 10 · It is a further object of this invention to prevent interference by the standing waves by locating the signal-receiving apparatus at a node of the standing waves established by the sending apparatus.
- 15 · By making use of two sets of standing waves, simultaneous signaling in two directions over the same wire may be accomplished. The signal-sending apparatus and the signal-receiving apparatus at the same 20 station are separated by a quarter-wavelength of the energy from the sending apparatus at that station. Consequently, the receiving apparatus is at a node of these waves.
- 25 · While my invention is directed primarily to the location of potential-responsive apparatus at the nodes of such standing potential waves, the location of current-responsive apparatus at the nodes of current waves also 30 comes within the scope of my invention.

The invention may be better understood by reference to the following description and the accompanying drawing, in which the single figure is a diagram illustrating 35 the principle thereof.

The invention is illustrated as applied to a line 1, which may, for example, be a transmission line, that is parallel to the ground 2, but it is equally applicable to a plurality 40 of lines, and to a completely metallic circuit, whether or not it is grounded.

At one station, the sending apparatus 3 comprising means for generating and modulating high-frequency energy, is connected 45 to the line 1, preferably by means of a condenser 4. This enables the line 1 to be used for purposes other than signaling. It may, for example, serve as a power line. The energy delivered to the line 1 by the sending 50 device 3 will give rise to standing waves which are diagrammatically represented by the curved line 5. Assuming that the sending device 3 is of a type which causes poten-

tial changes at the point where it is connected to the line, the curve 5 will represent a 55 standing wave of potential.

The invention is equally applicable to sending apparatus which impresses current upon the line. In such an application, the curve 5 will represent a standing current-wave and the connection would be either direct or by means of a transformer.

The curves in the figure show but a single wave length between stations. In the practice of the invention, the distance will usually be more than this and, often, it may be 65 many times as great.

The wave represented by the line 5 will have a loop at the sending apparatus 3, although this apparatus need not be at the 70 exact center of the loop. Nodes of the wave represented by the line 5 occur at half-wavelength intervals along the line 1. At the point 6, which is one of these nodes adjacent to the sending device 3, a receiving device 7 is connected to the line. This connection is illustrated as made by means of a condenser 8, but other ways of making the connection are contemplated.

Because the point 6 is a node of the waves 80 5, little energy from the sending device 3 reaches the receiving device 7. The receiving device, is therefore, unaffected by the adjacent sending device, and the signals sent from the device 3 do not interfere with 85 reception of other signals by the receiver 7.

The sending device 3 and the receiving device 7, together constitute a station. A second station, having a sending device 9 and a receiving device 10 that are connected to 90 the line 1 by condensers 11 and 12, respectively, is represented in the drawing. The connection to the sending device is shown at a node of the wave 5, but this location is not a necessary feature of the system. It is however, desirable, because the wave 5 will be less distorted by the sending device 9 if the connection to the line is made at a node.

The standing wave on the line 1, caused by energy from the sending device 9, will 100 have a loop adjacent to the connection to this sending device, although the connection generally will not be at the exact center of the loop. This standing wave is represented by the curve 14. This wave has 105 nodes at each half-wave-length, of course,

but its wave-length is not necessarily or usually the same as the wave-length of the standing wave represented by the curve 5.

The connection to the receiving device 10 5 is located at a quarter-wave-length from the sending device 9 so that the energy from the sending device 9 cannot affect the receiving device 10.

The wave-lengths of standing waves upon 10 a line depend upon the frequency and upon the characteristics of the line. The distributed inductance and distributed capacity are the characteristics of the line which have the greatest effect upon the length of the 15 standing waves. These characteristics are very nearly constant; consequently, once the instruments have been tuned, further adjustment is not needed.

It is evident that, when geographical considerations fix the distance between a sending device and its neighboring receiving device, this distance may be made a quarter-wave-length by adjustment of the frequency.

It will be evident to those skilled in the 25 art that my invention is not limited to the use of only two sets of standing waves and also that many variations of detail, beside those explicitly mentioned above, may be made without departing from the spirit of 30 this invention, which is not limited except as required by the prior art or indicated in the claims.

I claim as my invention:

1. A carrier-current system of radio frequency signaling comprising a transmission line and a plurality of sending and receiving stations, each of said stations comprising a sending apparatus adapted to excite said transmission line by producing stationary loops and nodes of high-frequency potential thereon and each station also comprising a receiving apparatus energized from said transmission line at a point which is a potential node for the energy delivered 45 by the sending apparatus of the same sta-

tion, and not a potential node for energy delivered by the sending apparatus of another station.

2. In a high-frequency signaling system, a line, two signal-sending devices for impressing high-frequency energy upon said line at a distance apart greater than a half-wave-length and a receiving device adjacent each signal-sending device, each signal-receiving device being at a quarter-wave-length from the adjacent signal-sending device.

3. In a high-frequency signaling system, a line, a signal sending device for impressing high-frequency energy upon the line to 60 cause standing waves thereon, an adjacent signal-receiving device at a quarter-wave-length from said signal-sending device and a distant signal-receiving device at approximately an even number of quarter-wave-lengths from said signal-sending device whereby the neighboring signal-receiving device will be insensitive to the energy sent out by said sending device and the distant signal-receiving device will be responsive to said energy.

4. In a high-frequency signaling system, a line, two signal-sending devices for impressing high-frequency energy upon said line at a distance apart greater than a half-wave-length, two signal-receiving devices, each at a quarter-wave-length from the adjacent signal-sending device and at approximately an even number of quarter-wave-lengths from the distant signal-sending device, whereby each signal-receiving device is insensitive to the energy from the adjacent signal-sending device and responsive to the energy from the distant signal-sending device.

In testimony whereof, I have hereunto subscribed my name this 27th day of March, 1924.

DONALD G. LITTLE.
